(57) **CLAIM**

The ornamental design for a kick stand, as shown and described.

DESCRIPTION

FIG. 1 is an isometric view of a first embodiment of a kick stand according to the present invention;

FIG. 2 is a first side elevation view of the first embodiment of the kick stand;

FIG. 3 is a second side elevation view of the first embodiment of the kick stand;

FIG. 4 is a top plan view of the first embodiment of the kick stand;

FIG. 5 is a bottom plan view of the first embodiment of the kick stand;

FIG. 6 is a first end elevation view of the first embodiment of the kick stand;

FIG. 7 is a second end elevation view of the first embodiment of the kick stand;

FIG. 8 is an isometric view of a second embodiment of a kick stand according to the present invention;

FIG. 9 is a first side elevation view of the second embodiment of the kick stand;

FIG. 10 is a second side elevation view of the second embodiment of the kick stand;

FIG. 11 is a top plan view of the second embodiment of the kick stand;

FIG. 12 is a bottom plan view of the second embodiment of the kick stand;

FIG. 13 is a first end elevation view of the second embodiment of the kick stand;

FIG. 14 is a second end elevation view of the second embodiment of the kick stand;

FIG. 15 is an isometric view of a third embodiment of a kick stand according to the present invention;

FIG. 16 is a first side elevation view of the third embodiment of the kick stand;

FIG. 17 is a second side elevation view of the third embodiment of the kick stand;

FIG. 18 is a top plan view of the third embodiment of the kick stand;

FIG. 19 is a bottom plan view of the third embodiment of the kick stand;

FIG. 20 is a first end elevation view of the third embodiment of the kick stand; and,

FIG. 21 is a second end elevation view of the third embodiment of the kick stand.

The broken lines shown in the figures are for illustrative purposes only, and form no part of the claimed design.
